UNITED STATES PATENT OFFICE.

LEIGH M. GRIFFITH AND FRANK A. GARBUTT, OF LOS ANGELES, CALIFORNIA.

SCORE-BOARD.

1,171,715.

Specification of Letters Patent.

Patented Feb. 15, 1916.

Application filed November 5, 1913. Serial No. 799,414.

To all whom it may concern:

Be it known that we, LEIGH M. GRIFFITH and FRANK A. GARBUTT, both citizens of the United States, residing at Los Angeles, in 5 the county of Los Angeles and State of California, have invented a new and useful Score-Board, of which the following is a specification.

Our invention relates to score boards by 10 means of which it is possible to illustrate the progress of a baseball game which has taken place at a distance and from which reports have been received by telegraph or otherwise.

15 The principal object of our invention is to provide such a board upon which the position of all the players may be indicated by suitable units at all times and upon which the position of these units may be changed 20 at will and the actual movement of the units being directly visible to the spectator.

A further object is to provide such a board upon which the position of the ball 25 will be illustrated by a suitable unit at all times and upon which it will be possible to show the movement of this unit.

A further object is to provide means for indicating to which of the contesting teams any particular unit belongs.

30 A further object is to provide means whereby the greatest flexibility of illustration will be provided and upon which nearly all plays common to the game of baseball may be clearly illustrated.

35 Further objects and advantages will appear hereinafter.

Referring to the drawings which are for 40 illustrative purposes only: Figure 1 is a front view of such a score board. Fig. 2 is a rear view showing the various playing units in position. Fig. 3 is a perspective view of a player unit. Fig. 4 is a section through such a player unit. Fig. 5 is a front view of a ball unit. Fig. 6 is a front 45 view of the bat and its operating mechanism. Fig. 7 is a sectional view of the parts shown in Fig. 6. Fig. 8 is a diagram of connections. Fig. 9 is an alternative form of the player unit. Fig. 10 is a cross section 50 through that unit.

The fundamental principle upon which this board works is as follows: A sheet of translucent glass 1 is placed in an opaque

frame 2, this glass having an outline of a baseball diamond marked on its face and 55 being covered with some liquid, such as glycerin, upon its back. A series of player units 3 and a ball unit 4 are fastened on the rear side of the glass 1 by means of vacuum cups 5. The vacuum cups 5 serve to attach 60 the players and the ball to the glass in any position, the action of the vacuum cups being assisted by the glycerin which also serves as a lubricating means making it possible to move the players without exerting 65 undue force. The player units 3 and the ball unit 4 are internally illuminated, the lights shining through openings 6, 7, and 8 which are immediately in contact with the glass 1 when the units are secured to the 70 glass. This results in an illuminated spot upon the glass 1 which is plainly visible from the front of the board and which moves from place to place as the ball and player units are manipulated manually from the 75 back.

In the embodiment of our invention illustrated in the drawings the glass 1 is supported in the frame 2 and this frame has a series of openings 10 in which the score by 80 innings may be kept, and a pair of openings 11 in which the name of the contesting teams may be placed, red lights 12 and green lights 13, which indicate the colors used to designate the respective teams, a 85 series of openings 14 in which the names of the various players may be displayed, a series of openings 15 in which the names of the umpires may be displayed, and a pair of openings 16 in which the name of 90 the man at bat may be shown, the method of displaying such names or numbers being common in the art of constructing such score board and consisting of providing an opening in the board and inserting a lettered or numbered card at the rear of said opening so that the lettering or numbering is visible from the front of the board. The names or numbers in these openings may be changed at will by the operator of the 100 board from the rear.

A series of colored lights 17, 18, and 19 are provided for indicating the number of balls or strikes of the batter and the number of put outs of the side at bat. It will 105 be noticed that two openings 16 are pro-

vided for the man at bat, and these openings may be used either to indicate the fact that the batter is right or left handed or the team to which he belongs.

- 5 On the front side of the glass 1 is painted in black a baseball diamond 20 having bases 21, 22, 23, and 24, and base and foul lines as clearly indicated in Fig. 1. Close to the front of the board on either side of 10 the home base 24 are located two standards 25 which have a pin 26 projecting inwardly therefrom upon which are located the bats 27, these bats being between the standards 25 and the face of the board. A rod 28 is 15 pivoted to an extension 29 on the bat 27 and extends downwardly and carries a pin 30 which has a spring 31 attached thereto, the other end of the spring 31 being fastened in an eye 32 screwed to a frame 33 of the 20 score board. The bat 27 may be rotated about the pin 26 by pressing downward upon the pin 30 against the action of the spring 31, thus throwing the bat 27 in view directly over the home base 24. Either of 25 the bats may be operated at will for the purpose of indicating a right or left handed player.

The player units 3 are illustrated in Figs. 3 and 4, consisting of a case 35 having a 30 series of ventilated openings in the back and a pair of ventilated openings 37 in the top. The slots 6 and 7 are provided in a front 38 which is covered with a sheet of soft felt 39. The opening 6 has a sheet of 35 green glass, and the opening 7 has a sheet of red glass behind it. A partition 40 divides the interior of the player unit 3 into two compartments, one of these having the opening 6 and the other the opening 7 in 40 the front. Incandescent lamps 41 in sockets 42 are placed in each of these compartments and serve to illuminate the slots 6 and 7, one of these slots being ordinarily illuminated at one time producing a red or green 45 slot as the operator desires. A pair of brackets 43 are secured to the top of the player unit 3 and carry a pair of soft rubber vacuum cups 44 by means of which the player unit is fastened to the glass 1, this 50 glass being normally thickly coated with glycerin or a similar liquid 45. A connection cable 46 enters the player unit 3 and serves to furnish current to the lamps, any suitable form of switch 47 being also 55 incorporated therein for purposes to be described. The ball unit 4 is similar to the player unit 3 having vacuum cups 5 as illustrated in Fig. 5 but having only a single lamp therein and having a circular 60 hole 48 therein through which this light shines. This hole 48 may be covered with yellow glass, or any distinctive color may be used therein. It is evident that as the ball unit and the player units are attached 65 to the back of the glass that brightly illumin-

nated spots may appear on the front of the glass due to the light shining through the openings 6, 7, or 8.

The diagram of connections shown in Fig. 8 illustrates the electrical connections 70 of the board. In this diagram 50 and 51 are wires connected to some source of electrical supply. An interrupter 52 is provided which may be either coil actuated or motor driven and which serves to supply 75 current intermittently to a wire 53. The wire 51 is connected to a switch 54 through which it may be connected to either of wires 55 or 56 as the operator may desire.

Nine player units are used to represent the 80 team in the field, these player units being represented diagrammatically by lamps 57 and 58, there being nine of these lamps each connected to the wires 50, 55, and 56. Four base runners are provided, one of these base 85 runners being indicated diagrammatically by lamps 59 and 60. A wire 61 from a common connection of these lamps connects to a switch 62 which is adapted to connect the center pin of these lamps to a wire 63 or 64. 90 The wires from the lamps 57 and 58 may be designated as 65, 66, and 67. The switch 62 may be of any convenient form such as that illustrated at 47 in Fig. 4. Wires 68 and 69 extend from the outer terminals of the 95 lamps 59 and 60. The ball is represented diagrammatically by a lamp 70 which has one terminal connected to a wire 71 which is connected to the wire 51. The other terminal 72 of the lamp is connected to the center 100 of a switch 73 which is adapted to connect the terminal 72 to either a wire 74 or 75. The lamps 12 and 13 are connected by means of wires 76 and 77 to the wires 50 and 51 through a switch 78. The wires 50 and 51 105 extend downwardly, the wire 51 being connected to one terminal of the lamps 17, 18, and 19, and the wire 50 being connected to a series of switches 79, 80, and 81 by means of which these lamps may be severally 110 thrown in circuit.

The method of operation of our invention is as follows: The nine player units, one of these units being represented in the diagram by the lamps 57 and 58, are placed 115 in the back of the board, out-fielder unit being indicated at 82, short stop at 83, base men at 84, the pitcher at 85, and the catcher at 86. The ball unit 4 is placed directly behind a painted rectangle 87 which represents the pitcher's box. A player unit 88 representing the batter is also moved into place on the back of the board. This batter unit 88 is represented in the diagram by the lamps 59 and 60 and has the switch 62 120 thereon. The ball unit 4 is represented in the diagram by the lamp 70. The switch 54 is thrown in contact with the wire 64 and the switch 73 is thrown into contact with the wire 74. Switches 79, 80, and 81 are left 130

in their open position. It will be noted with the connections in this order that the lamps 57, 59, and 70 are illuminated through their respective wires, the lamp 57 being green, the lamp 59 being red, and the lamp 70 being yellow. The lamps 12 and 13 are also illuminated when the switch 78 is closed, the lamps 12 being red and the lamps 13 being green. There will of course be nine of the green lamps and the player units 82, 83, 84, 85, and 86 will be represented by illuminated green spots upon the face of the board. The batter unit 88 will be represented by the lamp 59 which will show red on the face of the board. Additional runner units are provided so that the position of men on the bases can be readily indicated. When the team represented by the green lights is retired the switch 54 is thrown over into connection with the wire 55 and the lamps 57 and 59 are disconnected, and the lamps 58 and 60 are connected in circuit, the lamp 58 being red and the lamp 60 being green. This changes the color of the player units 82, 83, 84, 85, and 86 and indicates that the other side has gone in the field, the batter unit 88 also being changed in color to green. The switch 54 being in its first position connected to the wire 56, the units 82, 83, 84, 85, and 86 being green and the batter 88 being red, the operator moves the ball unit 4 from the pitcher's box 87 to the catcher 86. Should the batter strike at the ball the operator presses downwardly upon the pin 30 and causes the bat 27 to fly up across the home base 24. At the same time by depressing the switches 79 and 80 he registers a ball or a strike against the batter providing he does not hit the ball fairly. Should the batter 88 hit the ball fairly the operator moves the ball 4 into the position that the ball would take. Should the ball be caught by any of the opposing players it is moved up proximately to that player. Should the player fail to catch it for any reason the switch 73 is moved connecting the wire 72 with the wire 75 which is connected with the wire 53 which supplies an intermittent current to the lamp 70 causing it to flicker rapidly. Simultaneously with such a movement of the ball the batter 88 is moved downwardly toward the first base 21, the switch 62 being moved over to connect with the wire 63 thus supplying an intermittent current to the lamp 59 and causing it to flicker. This flickering of the lamp which represents the runner produces the illusion of movement. A flickering lamp moved slowly producing an impression of rapid movement. Some operators prefer to manipulate the ball switch 75 in the same manner using the flickering of the light 70 to indicate a movement of the ball rather than an error on the part of the opposing player. Should the batter 88 reach first base 21

safely the unit 3 representing the player 88 is left in position near first base and may be moved off the base representing the natural movement of the player in the real game. It is possible to represent a movement of the ball 4 to any of the base men 84, to the catcher 86, or in fact to any position on the diamond by an actual movement of the spot of light 4 representing that ball.

In the modification of the player unit 75 shown in Figs. 9 and 10, 90 is a case provided with a cover 91 in which there is a slot 92. Behind this slot and inside the case is a slide 93 composed of two colors of glass, such as red and green, and provided with an operating pin 94 sliding in a slot 95 in the bottom of the case 90. The slide 93 may be moved back and forth by means of the pin 94 so that either red or green glass may be placed behind the slot 92. Inside the case is a lamp 96 mounted in a socket 97 furnished with current from a storage battery 98 through a switch 99. A pair of vacuum cups 100 held in standards 101 are provided on the top of the unit for the purpose of securing it to the glass. This unit may be used independently of any wiring, the slides being shifted to indicate which side is at bat or in the field. The switch 99 is used for disconnecting the lamp 96 from the battery 98 when not in use.

What we claim is:—

1. In a score board, a vertical glass member, opaque markings on said glass member representing the markings of a base ball field, illuminated units behind said glass member representing the players and ball, and means whereby said units can be secured and supported on the back of said glass member in such a manner that the units can be freely slid from place to place on said glass member without being detached therefrom.

2. In a score board, a vertical glass member, opaque markings on said glass member representing the markings of a base ball field, illuminated units behind said glass member representing the players and ball, and vacuum means whereby said units can be secured and supported on the back of said glass member in such a manner that the units can be freely slid from place to place on said glass member without being detached therefrom.

3. In a score board, a vertical glass member, opaque markings on said glass member representing the markings of a base ball field, illuminated units behind said glass member representing the players and ball, vacuum means whereby said units can be secured and supported on the back of said glass member in such a manner that the units can be freely slid from place to place on said glass member without being detached therefrom, and a thin film of lubri-

cating material over the back surface of said glass member said film serving to reduce the friction as the units are slid from place and also serving to prevent the vacuum from being broken in said vacuum means due to leakage between said vacuum means and said glass member.

5 In testimony whereof, we have hereunto

set our hands at Los Angeles, California,
this 25th day of October, 1913.

LEIGH M. GRIFFITH.
